SHARPENING DEVICE

Clarence Raymond Ellis, Sausalito, Calif.

Application April 29, 1939, Serial No. 270,857

2 Claims. (Cl. 51—80)

This invention relates to improvements in sharpening devices and has particular reference to a device for sharpening screwdrivers, and more particularly to screwdrivers used by jewelers.

5 The principal object of this invention is to produce a device which will sharpen a screwdriver evenly on both sides thereof, and also a device which will square the end of the screwdriver, thereby permitting the same to seat evenly

10 in the bottom of the screwhead slot.

A further object of this invention is to produce a device of this character which is simple to operate, economical to manufacture and one which will accommodate screwdrivers of various sizes and yet produce a uniform result, irrespective of the size of the screwdriver.

15 A further object is to provide means for limiting the end grinding action when facing the end of the screwdriver after the sharpening operation.

20 Other objects and advantages will be apparent during the course of the following description.

In the accompanying drawings forming a part of this specification and in which like numerals 25 are employed to designate like parts through the same,

Fig. 1 is a side elevation of my device.

Fig. 2 is an end elevation looking from the left of Fig. 1.

30 Fig. 3 is a side elevation showing portion thereof broken away in order to illustrate the mechanism.

Fig. 4 is a top plan view of Fig. 2.

Fig. 5 is an enlarged fragmentary detailed view, 35 showing the sharpening operation.

Fig. 6 is an enlarged fragmentary detailed view, showing the end grinding operation and

Fig. 7 is a fragmentary detailed view, showing the rear arrangement.

40 Screwdrivers rapidly become bent, burred, chipped and otherwise deformed. It is therefore necessary to resharpen the bit, in order to have it properly function, and without marring the head of the screw upon which it is used.

45 Applicant has devised a sharpening device which will grind the opposite sides of the bit evenly with relation to the axis of the screwdriver, which is very important, particularly when dealing with minute screws such as are used in a jeweler's trade; and applicant has further provided a device wherein the end of the screwdriver, after being sharpened, is round, square or, in other words, faced, so that it will properly seat in the slot of the screw.

50 In the accompanying drawings wherein for

the purpose of illustration is shown a preferred embodiment of my invention, it will be noted that my device consists of a base 5, which is preferably rectangular in shape and forms a convenient means for mounting my device in a vice commonly used on jewelers' benches. Upon this base is secured a rectangular housing 6, the front of which is open, as shown in Fig. 2. Slidably mounted in the housing 6 is a carrier 7, which carrier is pressed upwardly by a spring 8, interposed between the bottom of the housing 6 and the bottom of the carrier 7. Counteracting the tension of a spring 8 is a threaded member 9, having a knurled head 11, through the medium of which the screw member 9 may be adjustably rotated to move the carrier 7 against the tension of the spring 8.

55 Mounted in the carrier 7 is a shaft 12, upon which is secured a driving gear 13 and a grinding wheel 14. A shaft 16 is journaled in the housing 6 and passes through slots formed in the carrier 7, and has mounted thereon a gear 17, which meshes with the gear 13. The shaft also carries a grinding wheel 18. This shaft may be driven in any convenient manner, but I have here shown 20 a crank handle 19 rotating the same.

60 Secured to the front of the housing 6 is an extension 21, which serves to position the bifurcated end of a tool carrier 22. The carrier 22 comprises a flat base portion 22a having one end removably pivoted to the housing at 21. From each side edge of the flat base portion extends a side portion 22b, these side portions being parallel. The upper end of this tool carrier extends through a slot 23, formed in the top of the housing 6.

65 Mounted in the carrier is a tool holder 24, in which is formed bores 26, 27, 28 and 29. This tool holder is mounted upon stub shafts 31, which ride in inclined slots 32, formed on the opposite sides of the tool carrier. The tool holder is in the form of a block having parallel side faces and fits snugly between the sides 22b of the carrier. Moreover, the block forming the tool holder has a square periphery and the stubshafts or pins 31 are fixed in the block in the centers of its side faces so that the block may be slid outwardly and inwardly to and from the carrier base 22a and when slid outwardly it may be rotated. By this means a selected peripheral side of the block 50 may be engaged against the base 22a. The base 22a is provided with an opening 22c and when a selected side of the tool holder engages the base a respective bore will align with the hole or opening 22c. The several bores are of different 55

diameters to accommodate different diameters of screwdrivers and by the means just described, a selected bore may be aligned with the opening 28c for the reception of the screwdriver to be presented. This arrangement permits the tool holder to be moved away from the grinding wheels, so as to be rotated, as indicated in dotted lines in Fig. 1, the purpose of which will be later seen.

10 It is also to be noted here that the edge faces of the tool holder are each provided with an inclined groove 33, the purpose of which will be later seen.

15 The tool carrier is provided with a slot 34, as best illustrated in Figs. 5 and 6, the slot being of sufficient horizontal width to accommodate the widest screwdriver which may be sharpened in the device. The slot is formed by striking the metal so as to form curved lips 36, separated 20 from each other a predetermined distance, the purpose of which will be later seen.

18 The operation of my device is as follows:

Assuming that the parts have been assembled, as shown in Figs. 1 and 2, and it is desired to 25 sharpen a screwdriver, the same is placed through one of the bores, as, for instance, the bore 26, and assuming the same is the proper size to accommodate the particular screwdriver to be sharpened. When the screwdriver is in place, as 30 shown in Fig. 5, the point thereof will come to rest between the grinding wheels 14 and 18.

35 The operator now presses the thumb against the thumb piece A of the screwdriver, and the first finger is placed at approximately the point B on top of the tool holder. The crank 19 is now rotated in a clockwise direction, while the first finger moves the carrier back and forth, as indicated by the double ended arrow of Fig. 2, thus moving the screwdriver bit back and forth 40 across the stone during the sharpening operation, which serves to prevent grooving of the stone.

45 After the bit has been ground a sufficient amount, the tool as a whole is removed from the holder and laid in the groove 33 on the top of the holder, as illustrated in Fig. 6, with the point of the bit extending through the slot 34 and into

engagement with the wheel 18. By again rotating the crank 19 the end of the bit will be ground away until the distance between the curved lips 36 prevent further movement of the bit toward the grinding wheel.

5 It is, of course, understood that the tool carrier is moved back and forth in the same manner to cause the bit to travel across the full face of the grinding wheel, as previously described for the sharpening operation.

10 It will thus be seen that I have produced a device which will accomplish all the objects above set forth.

15 It is to be understood that the form of my invention herewith shown and described is to be taken as a preferred example of the same and that various changes relative to the material, size, shape and arrangement of parts may be resorted to without departing from the spirit of the invention or the scope of the subjoined claims.

20 Having thus described my invention, I claim:

1. In a sharpening device, a housing open at one side, a pair of adjacent grinding wheels mounted in said housing with their axes parallel to each other and equidistant from the open side thereof a tool carrier including a flat base portion having an opening therein and a pair of parallel side plates, said side plates having oppositely disposed slots extending outwardly from the centers of the plates, a tool holder having parallel sides and a square periphery and slidably and rotatably fitted between said side plates to have its peripheral sides selectively engageable against the carrier base portion, said holder being provided with tool positioning means for each side of the holder periphery alining with the base opening upon a selected side of the tool holder engaging said base portion, and pivot pins fixed in said tool holder at the center of its sides and engaging in said slots.

2. The sharpening device of claim 1 wherein the carrier has one end pivoted to the housing to permit swinging of the tool holder transversely of the grinding wheels.

CLARENCE RAYMOND ELLIS.
